for the Plaintiff

UNITED STATES PATENT OFFICE.

EDWARD BERNARD HESS AND LEWIS CARY MYERS, OF BROOKLYN, NEW YORK,
ASSIGNORS TO ROYAL TYPEWRITER COMPANY, INC., OF NEW YORK, N. Y.

CARRIAGE-RELEASE MECHANISM FOR TYPEWRITING MACHINES.

1,415,032.

Specification of Letters Patent.

Patented May 9, 1922.

Original application filed January 13, 1921, Serial No. 436,924. Divided and this application filed May 27, 1921. Serial No. 473,166.

To all whom it may concern:

Be it known that we, EDWARD BERNARD HESS and LEWIS CARY MYERS, both citizens of the United States, residing in Brooklyn, county of Kings, city and State of New York, have invented certain new and useful Improvements in Carriage-Release Mechanism for Typewriting Machines, of which the following is a specification.

10 In our application for patent filed January 13, 1921, No. 436,924, we have shown all of the mechanism of a typewriting machine embodying various improvements made by us to provide a small, compact and light 15 machine which is portable, in which the parts can be easily assembled and which may be made and sold at a relatively low cost. The application for the present patent is a division of the said application filed January 13, 1921, and the claims herein are confined to certain improvements in the carriage release mechanism.

The object of this invention is to provide what may be termed an integral carriage 25 rack bail, the rack bar, its supporting arms, its lifting levers and its stops being all assembled and connected in such manner that they may be readily placed in position in the machine and connected with the carriage in 30 assembling the mechanism and may as readily be withdrawn from the carriage when desired.

In the accompanying drawings,

Figure 1 is a view partly in side elevation 35 and partly in section of parts of a typewriting machine with our improvements applied;

Figure 2 is a perspective view of the carriage rack bar (with parts broken away), 40 its lifting levers, stops and supporting arms;

Figure 3 is a detail view in section, showing how the rack supporting arm on one end of the rack is pivotally connected with the carriage.

45 In Figure 1, A indicates part of the typewriter frame, B one end of the carriage, C the platen, and D parts of the escape mechanism. The rack bar is indicated in Fig. 1 at E, and a paper release lever at F.

50 As shown in Fig. 2, the rack bar has its opposite ends bent to form arms e, which are disposed at right angles to the toothed portion of the bar. These arms are perforated

at e' to receive pivot screws, which connect them with the opposite side plates of the carriage. The arm e at the right-hand end of the bar is connected with the carriage in the manner indicated in Fig. 3, where B indicates the side plate of the carriage, F a paper release lever, G a pivot screw and H a spacing sleeve. A reduced portion of the sleeve H is riveted to the plate B at b, and the sleeve is internally threaded to receive the pivot screw F'. The inner end of the screw F' is reduced and shouldered at c and 65 enters the hole e' in the adjacent rack supporting arm e. The screw is shouldered at f to receive the paper release lever F, which is held in place by the head of the pivot screw F', but is free to turn on the part f 70 of the sleeve.

The arm e on the opposite end of the rack bar is pivoted to the adjacent end plate of the carriage in any suitable way.

Carriage release levers K and L are connected with the rack bar and are employed for lifting the rack bar out of engagement with its operating pinion d. The lever L is formed integrally with an arm l, which is riveted to one end of the rack bar and this arm is formed with a stop l', which serves to limit the movement of the rack bar when it returns to normal position to engage the pinion d. The lever K is likewise formed integrally with an arm k secured to the 85 opposite end of the rack bar and this arm carries a stop k', similar to the stop l' and serving a similar purpose. The arm k is formed with a lug k², to which is attached a spring M (Fig. 1), which serves to return 90 the rack bar to normal position in engagement with its pinion.

In this way we provide what may be termed an integral carriage rack bail, the rack bar, its supporting arms, its lifting 95 levers and its stops being all assembled and connected in such manner that they may be readily placed in position in the machine and connected with the carriage in assembling the mechanism and may as readily be 100 withdrawn from the carriage whenever desired.

We claim as our invention:

1. A rack bail for typewriting machines, comprising pivotally mounted side arms extending from the rack bar and a lever at.

2
each end of the bar formed integrally with a stop for limiting the movement of the bar and which is secured to the end thereof.

2. In a typewriting machine, the combination of a rack bar having arms pivotally connected with the machine frame and a lifting lever for the rack formed integrally with a stop attached to the rack bar and formed also with a lug for supporting a spring which returns the rack to normal position.

3. The combination with a carriage frame of a paper release lever, a rack bar having arms pivotally connected with the carriage frame, a lifting lever for the rack bar formed integrally with a stop attached to the rack bar, and means for pivotally connecting the paper release lever and one arm of the rack bar to the carriage frame, comprising a

shouldered spacing sleeve interposed between the paper release lever and the side of the carriage frame, a headed screw for holding the paper release lever on the shouldered sleeve and which has a portion projecting from the side plate of the carriage to which 25 one arm of the rack bar is pivoted.

4. In a typewriting machine, a toothed rack bar formed integrally at each end with a supporting arm and a rack lifting lever formed integrally with an arm secured to 30 one end of the rack bar and which is formed integrally with a bent portion forming a stop to limit the downward movement of the rack bar.

In testimony whereof, we have hereunto 35 subscribed our names.

EDWARD BERNARD HESS.
LEWIS CARY MYERS.
